UNITED STATES PATENT OFFICE.

JOHN L. RIEGER, OF SANDUSKY, OHIO.

SHIPPING-CASE.

1,100,099.

Specification of Letters Patent. Patented June 16, 1914.

Application filed September 18, 1913. Serial No. 780,623.

To all whom it may concern:

Be it known that I, JOHN L. RIEGER, a citizen of the United States, and a resident of Sandusky, in the county of Erie and State of Ohio, have invented a certain new and useful Shipping-Case; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to shipping and packing cases, and particularly to cases or containers of this class constructed of fiber or paper board, but is not restricted to such use as it may be used for any purpose for which it may be adapted or appropriate.

The object of my invention is the provision of an improved case of the character described, which is strong and durable in its construction, and capable of being easily and quickly set up and sealed and of opening at one side only thereof, thus insuring the placing of the case in upright position before opening, which in itself is quite an important feature in shipping cases, as it frequently occurs that the shipping address is placed on the bottom instead of the top of cases of this class so that when opened on the addressed side the package or individual containers therein are in inverted position.

A further object of my invention is the provision of a single-piece body blank for cases or containers of this or similar character, which blank is capable of being easily and quickly set up or knocked down and secured in folded or set-up form, whereby to facilitate shipping and to enable a compact packing of the cases when not in use.

The invention is fully described in the following specification, and while, in its broader aspect, it is capable of embodiment in numerous forms, a preferred embodiment thereof is illustrated in the accompanying drawings, in which,—

Figure 1 is a perspective view in closed and sealed form of a case embodying the invention. Fig. 2 is a perspective end view thereof with the top open. Fig. 3 is a perspective view of an end portion of the case in partly assembled position and with the end reinforcing member separated therefrom. Fig. 4 is a plan of the body blank of

the case. Fig. 5 is a perspective view of the blank in partially folded form, and Figs. 6 and 7 are different modifications of the end reinforcing means.

Referring to the drawings, A designates the bottom, B, B the sides and C, C the ends of a case or container embodying the invention, the sides and ends being attached to the bottom along scored or weakened lines 1 and 2, respectively.

Each end C is provided at its outer edge with an end flap D, preferably equal in width to the end and of a length or depth suitable to enable its free outer edge to lap the other end flap when the blank is in folded form, and each flap is divided by a score line 3 into the parts a, b. The opposite end edges of each end C are provided with extensions E, which attach to the ends along respective scored or weakened lines 4 and are preferably, but not necessarily, of rectangular form. These extensions are preferably equal in their different dimensions to the widths or depths of the sides B and ends C respectively, and are separated from the respective end edges of the sides B by slits 5.

A tongue c projects outwardly from the inner end portion of each extension E at the adjacent side edge of the respective flap D, being separated therefrom by a slit 6, and is preferably substantially equal in width and length to the width and length, respectively, of the part a adjacent thereto. A score line 7 connects each extension E with its tongue c.

Foldably connected to the outer edge of each side B along a score line 8 is a side-flap F, and a tongue d at each end thereof, the tongues and flap being separated by slits 9. The side flaps F, F are of suitable width for them to overlap one another when the case is set up, as hereinafter described, and the tongues d are substantially equal in width to the tongues c.

In setting up or folding the blank to form a case the ends C, C are first placed in upright positions and the extensions E turned inwardly at right angles thereto to stand upright over the respective end portions of the score lines 1, 1, thus serving as inner braces for the ends. The tongues c at the same end are also folded one over another, as best shown in Fig. 5, and stapled, glued or otherwise suitably secured together to retain the extensions E in their folded positions. The sides B, B are next raised to

their upright positions and the tongues *d* folded down over the respective sets of connected tongues *c*, with adjacent tongues *d* overlapping and secured one to the other 5 in any suitable manner, or to the tongues *c*, to retain the sides in set-up position. The parts *a* of the end flaps *D* are then folded down flat over the respective tongue sets *c-d*, and may be secured thereto by gluing, 10 stapling, or in any other suitable manner. This leaves the side flaps *F*, *F* and the parts *b* of the end flaps *D*, *D* free to have closing or opening movements relative to the open top of the case, as shown in Fig. 2.

15 It will be understood that when the case is in folded or set-up position the extensions *E*, *E* extend the entire depth of the respective sides *B*, *B* and inward for a distance beyond the lapped tongue sets *c-d* to reinforce the end portions of the case against collapsing stresses, which is found to be quite an important feature.

In order to further reinforce and protect the end portions of the case from injury, I 25 preferably provide a skeleton member *G* for such purposes, as shown in Figs. 1, 2 and 3. This member is preferably in the form of a band of fiber or paper board, which band is angled or of L-shape in cross-section, 30 with its angle opening inwardly, and is of a shape and size adapting it to have a close sliding fit over an end of the case. The flange of the member which fits over the case end is substantially equal in width to 35 the part *a* of an end flap *D* to enable it to cover the same. While the members *G* may be secured to the case ends in any suitable manner, it is preferable to employ staples 10 with those at the top side extending 40 through the part *a* and underlying tongues *c-d*. The corners of the members *G* are preferably interiorly reinforced, by fiber, paper or metal, as shown in Fig. 3.

In Fig. 6 the end reinforcing members are 45 shown as comprising separate pieces *h*, *h* for fitting over the upper and lower edges of the case ends and covering the respective corners. In Fig. 7 the end protectors are 50 shown as comprising individual corner protectors *i*. In sealing the case preparatory to shipping same after being packed it is only necessary to place sealing strips 11 and 12 of any suitable material thereon, as shown in Fig. 1.

55 It is evident that I have provided a single-piece packing case body, which is inexpensive to manufacture, strong and durable in its construction and capable of being easily and quickly set up for use, and also 60 that the ends thereof are reinforced in a firm and secure manner, thus enabling the case to withstand hard usage in an efficient manner.

I wish it understood that my invention is 65 not limited to any specific construction or

arrangement of the parts except in so far as such limitations are specified in the claims.

Having thus described my invention, what I claim as new and desire to secure by Letters Patent, is,—

1. A case of the class described having ends, sides, a bottom and open top, with reinforcing extensions projecting from the ends interiorly of and against the end portions of the sides, tongues connecting the extensions in pairs across the end portions of the open top, tongues connecting the sides over said first tongues, and flaps hingedly connected to the upper edges of the sides 80 and ends for closing the open top.

2. A case of the class described composed of a single-piece body blank having ends, sides, a bottom and open top, with extensions projecting from the ends interiorly of 85 and against the end portions of the sides, tongues connecting the extensions in pairs across the end portions of the open top, tongues connecting the sides over said first tongues, and flaps hingedly connected to the 90 upper edges of the sides and ends for closing the open top.

3. A case of the class described having a bottom, sides, ends and an open top, with the ends hingedly connected to the bottom 95 and provided with extensions projecting interiorly of the case against respective end portions of the sides and connected at their top edges adjacent to the ends by tongues, flaps projecting from the top edges of the 100 ends and having hingedly connected parts with the inner part lapping over and secured to said tongues, and flaps projecting from the top edges of the sides for co-operating with the free parts of the end flaps to close 105 the open top.

4. A case of the class described, having a bottom, sides, ends and an open top, the ends being hingedly connected to the bottom 110 and having extensions projecting therefrom in contact with the adjacent end portions of the sides and connected at their top edges adjacent to the ends by tongues, tongues projecting from and connecting the end portions of opposing sides in lapping relation to said first tongues, a part projecting from the top edge of each end over and secured to the adjacent tongue set, and top closing flaps hingedly projecting from said parts and from the upper edges of the sides. 115

5. An article of the class described having a single-piece foldable body forming a bottom, sides, ends, and top closing flap, and members embracing the end portions of the body when in folded form to reinforce the 125 ends and to assist in maintaining the body in folded form, said members being of fibrous material.

6. An article of the class described having a bottom, sides, ends and an open top, ex- 120

tensions projecting from the ends in contact with the adjacent end portions of the sides and connected at their top edges adjacent to the ends by tongues, top closing flaps attached to the ends and sides, and means for telescoping the end portions of the article over portions of the end tongues whereby to reinforce the article ends.

7. A case of the class described formed of a single-piece body and having a bottom, sides, ends and an open top and top closing flaps hingedly connected to the upper edges of the respective ends and sides, means connecting the upper edges of opposed sides at the ends thereof, and means for reinforcing the ends of the body and securing a portion of each end flap over adjacent connecting means.

8. A case of the class described formed of a single-piece body blank having a bottom, sides, ends and top closing flaps hingedly connected to the upper edges of the sides and ends, extensions projecting from the ends within the case, tongues connecting the edges of said extensions in pairs adjacent to the ends, tongues projecting from and connecting the end portions of the sides at their upper edges in lapping relation to said first tongues, said end flaps having portions folded over and secured to said tongue sets, and reinforcing members telescopically engaging at the ends of the body and embracing the portions of the end flaps disposed over said tongues.

53 9. A body blank for cases of the class de-

scribed comprising a bottom panel, side and end panels hingedly connected to respective side and end edges of the bottom panel, end flaps hingedly connected to the edges of the end panels opposed to the bottom panel, extensions hingedly connected to the opposite ends of the end panels, tongues projecting from said extensions in adjacent parallel relation to the sides of the end flaps, and side flaps hingedly connected to the outer edges of the side panels.

10. A body blank for cases of the class described comprising a body panel and side and end panels hingedly connected to the respective side and end edges thereof, said side and end panels having side and end flaps hingedly projecting from the respective outer edges thereof and the end panels having extensions hingedly projecting from its opposite ends, tongues hingedly projecting from said extensions at the sides of the end flaps in adjacent position thereto, and tongues hingedly projecting from the outer edges of the side panels at the ends of the side flaps, said end flaps each having a score line extending crosswise thereof adjacent to its inner edge.

In testimony whereof, I have hereunto signed my name to this specification in the presence of two subscribing witnesses.
